SIDE DISCHARGE LOADING MECHANISM

Einar M. Arentzen, Franklin, Pa., assignor to Joy
Manufacturing Company, Franklin, Pa., a corporation of Delaware

Application April 28, 1938, Serial No. 204,842

10 Claims. (Cl. 198—7)

The present invention relates to an apparatus for discharging material laterally from a conveying or loading mechanism. The invention also includes means designed to compensate for the presence of obstructions located in the path of the discharge flow of material handled by the apparatus.

Although the principle of the invention is equally well applicable to the handling and conveying of many types of material, whether in bulk form such as coal or sand, gravel, stone, cinders, etc., or in packaged form, such as cans, boxes, etc., of merchandise; it is particularly suited for the handling of coal in mining operations. While not limited to use therewith, the device of the present invention is designed more especially for incorporation in a traveling mobile mechanical loader comprising a gathering mechanism and discharge conveyor such as shown and described, for example, in United States Patent No. 1,619,260, dated March 1, 1927. Such machines are usually self-propelled, either running on rails or mounted on a tractor as illustrated in the patent cited. Furthermore, the discharge conveyor may be mounted for swinging movement in various ways, one preferred and largely used construction being shown and described in United States Patent No. 1,785,402, dated December 16, 1930.

In the operation of such a loading machine, particularly in the relatively confined and often-time obstructed space available in coal mines, it is found necessary to convey the material around obstructions, such as mine timbers or props, and to change the direction of travel of the material through relatively sharp angles of 90° or greater. When a self-propelled gathering mechanism is moved through a "room" in a mine, there is very often found a series of mine timbers located between the discharge end of the mechanism and the apparatus which it is loading, such as mine cars or belt conveyors. The device of the present invention is accordingly, particularly adapted to transfer material from the discharge end of a moving gathering mechanism and conveyor to an adjacent conveying mechanism having a relatively fixed location with minimum interruption and inconvenience incident to the presence of intervening obstructions such as mine timbers and props. Additional objects and advantages of the invention shall become apparent as the following description proceeds.

To the accomplishment of the foregoing and related ends, said invention, then, consists of the

means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a top plan view of an apparatus embodying the principle of the invention, such apparatus being represented as in the process of operation in a mine; Fig. 2 is an end elevation of Fig. 1; Figs. 3 and 4 are fragmentary plan views illustrating two different positions occupied by the deflector plate of the side discharge mechanism with respect to an obstruction such as a mine timber; Fig. 5 is an enlarged, plan view of the side discharge mechanism having a portion of the conveyor deck broken away for convenience of illustration; Fig. 6 is an elevational view, partially in section, of Fig. 5; and Fig. 7 is a detailed sectional view taken substantially along lines 7—7 of Figs. 5 and 6.

Referring more particularly to Fig. 1 of the drawings, there is shown a loading machine of the type heretofore described as being illustrated in the two prior patents cited above. Such machine, in other words, comprises a self-propelled, track laying tractor 1 having a gathering apron 2 and gathering arms 3 and 4 mounted upon its forward end. An articulated conveyor 5 leads from such forward end to the rear of the loading and conveying mechanism, its discharge end 6 being capable of both vertical and horizontal swinging movement. The gathering and conveying mechanism consisting of the elements just described, is adapted to be moved forward into the pile of material A. The aforesaid Patent No. 1,785,402 may be referred to for fuller and more detailed explanation of the construction and mode of operation of the gathering and conveying mechanism consisting of the elements 1 to 6 inclusive.

In the installation shown, the coal being discharged from conveyor 5 is designed to be received on a conveyor B of the endless belt type, located in an entry way adjacent the space or room from which the coal is being loaded, and a series of roof-supporting posts C is interposed between such entry and room. The mechanism of present interest is designed thus to direct the discharged material from the conveyor 6 of the loading machine onto the belt B (or equivalent transporting means), irrespective of the interposed row of posts, where present, and irrespective of

whether such discharge is to be to the left or right side of the loading machine, as it advances.

Such special mechanism comprises, as a principal element, a rotatable disc 7 suitably supported at the outer end of the frame of the conveyor 6, so as to extend horizontally beyond the same just below such end. A deflecting plate 8, pivotally mounted at its inner end upon the axis of the rotatable disc 7, extends beyond the periphery of the latter and over the margin of the transport conveyor B. Such deflector plate 8 has an apron portion 9 which is slightly inclined from the horizontal and adapted to convey or lead material from the periphery of the disc 7 to the discharge point above the conveyor B. The inner end of the deflector plate 8 is in the form of a sleeve 10 adapted to fit over the upwardly extending end of the disc shaft or axle 11.

Assuming the disc 7 to be rotated in a clockwise direction, as indicated by the arrows in Figs. 1, 3 and 4, it will tend to carry the deflector plate around with it until the latter either strikes an obstruction such as a mine timber C, or the limit stop 15 on the discharge end of the articulated conveyor 5. As the tractor 1 moves forward, viz., in a right hand direction with respect to Figs. 1, 3 and 4, the deflector plate 8 on contacting a mine timber C is carried pivotally around in a counter-clockwise direction against the rotation of the disc 7. When the tractor 1 moves further, the end of the deflector plate 8 will clear the mine timber C and swing back to its original position and into the space between the next adjacent mine timbers. When the position of the rotatable disc 7 and the deflector plate 8 is such that the latter is moved too close to the end of the guard plate 12, so as to tend to choke off the discharge flow of material, it is merely necessary to swing the end 6 of the articulated conveyor 5 away from the mine timber a sufficient distance to permit the end of the deflector plate 8 to clear such timber. In such instance, the deflector plate 8 will again follow the rotating movement of the disc 7 to occupy its normal position again and on the other side of the obstructing timber being carried to such position by the weight of the material on the disc.

The guard plate 12 extends around a portion of the periphery of the disc 7 and has one end attached by means of a bolt or pin 13 to the side plate 14 of the conveyor 5. The limit stop arm 15 is similarly attached by means of a bolt or pin 16 to the other side plate 17 of the conveyor 5. A channel bracket 18 also supports the guard plate 12 at a point near the free or open end of the latter and is attached by means of a fastening stud 19 to the extension bed plate 20 and at a point in alignment with the shaft 11 of the disc 7.

It will be noted that the conveyor chain 21 carrying the scraping or conveying arms 22, which travel over the conveyor deck 23, extends around the end roller 24, and that the latter is adjustable in the slot 25 by means of take-up screws 26, this being for the purpose of adjusting the tension and tightness of the conveyor chain 21. In order to drive the disc 7, the under-run or return pass of the conveyor chain 21 engages with a sprocket 27 mounted upon the horizontal shaft 28, the latter being supported in the bearing bosses 29 and 30 on the bed plate 20. A beveled gear 31 meshes with a complementary beveled gear 32 mounted on the upper end of the vertical shaft 33 which is also mounted in the bed plate 20. The shaft 33 in turn carries a sprocket 34 which, through the chain 35, is connected to

the sprocket 36 upon the shaft 37. The sprocket 36 drives the gear 38 which in turn meshes with the idler gear 39. The latter meshes with the gear 40 carried by the disc shaft 11.

Thus the movement of the conveyor chain 21 operates to rotate the conveyor disc 7 in a clockwise direction (with respect to Fig. 5).

A secondary bearing mounting 41 is provided in the bed plate 20 for the purpose of converting the side discharge mechanism from a left hand to a right hand discharge. In this instance, the rotatable disc 7 is lifted over and mounted in the mounting 41 whereupon the gear 40 upon its shaft meshes directly with the gear 38. The direction of rotation of the disc 7 will then be in a counter-clockwise direction, as indicated by the arrow in Fig. 5. A deflector plate 8' which is in effect a "mirror image" of the deflector 8 is substituted for the latter. The positions of the guard plate 12 and limit stop arm 15 are of course reversed on the ends of the side plates 14 and 17 respectively, when the discharge is changed from the left hand to the right hand side of the mechanism. The channel bracket 18 is also changed to a position where its inner end is supported in alignment with the shaft mounting 41.

In conclusion, it should be explained that the general views of my improved side discharge loading mechanism which are found in Figs. 1 to 4 inclusive are diagrammatic in character. Furthermore, that in these views the rotary disc 7 is shown as having its axis aligned with the center of the swinging conveyor 6 whereas in the detailed views shown in the remaining figures such disc is located off-side, i. e., to the right or the left of the center line of the conveyor. The latter arrangement thus illustrated in detail is the preferred one, although in the case of small loading machines the construction diagrammatically shown in the first mentioned figures is simpler inasmuch as it will permit the disc to be more directly driven from the conveyor chain than where provision has to be made to reverse the direction of rotation of the disc.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a mechanism of the character described, the combination of a tractor mounting an endless conveyor, a rotatable disc mounted adjacent the discharge end of said conveyor and adapted to receive material therefrom, and movable deflecting means for guiding and clearing material from said disc during rotation, said deflecting means extending beyond the periphery of said disc and being adapted to be moved around the periphery of said disc on contact with an exterior object during travel of said tractor.

2. In a mechanism of the character described, the combination of a tractor mounting endless conveyor and a rotatable disc mounted adjacent the discharge end of said conveyor and adapted to receive material therefrom, movable deflecting means for guiding and clearing material from said disc during rotation, retaining means extending around a portion of the periphery of said disc for preventing the discharge of material from the surface thereof, driving mechanism for rotating said disc and means for connecting said driving mechanism to said con-

veyor, whereby movement of said conveyor operates to rotate said disc, said deflecting means extending beyond the periphery of said disc and being adapted to be moved around the periphery of said disc on contact with an exterior object during travel of said tractor.

5. In combination with a mechanical loader adapted to move along over the floor of a mine, an endless conveyor mounted on said loader, a rotatable disc mounted on said loader adjacent the discharge end of said conveyor and adapted to receive material therefrom, a deflector plate pivotally mounted on the axis of said disc and extending radially beyond the circumference of the latter and movable around said disc on contact with an exterior object during travel of said loader, a stationary guard plate mounted adjacent the periphery of said disc and extending around a portion thereof, one end of said guard plate being located adjacent the end of said conveyor and the other end of said guard plate terminating short of said deflector plate, driving mechanism for rotating said disc, and means for connecting said driving mechanism to said conveyor, whereby movement of said conveyor operates to rotate said disc.

4. In combination with a loading machine adapted to move over the floor of a mine and having a driven conveyor for transporting material to the rear of said machine, a side discharge device for said machine comprising a disc mounted for rotation about a substantially vertical axis at the discharge end of and at one side of the center of said conveyor, a deflector plate pivotally mounted above the said disc and extending beyond the periphery thereof, an apron carried by the extended portion of said plate and abutting against the periphery of said disc, said apron being adapted to be moved around the periphery of said disc on contact of said deflector plate with an exterior object during the travel of said loading machine, and means for rotating said disc.

5. In combination with a loading machine movable over the floor of a mine and having a driven conveyor for transporting material to one end thereof, a side discharge device for said machine, comprising a rotatable disc at the discharge end of and to one side of the center of said endless conveyor, a substantially vertical shaft mounted for rotation on said machine and on which said disc is mounted, a deflector plate journaled on said shaft above said disc and extending beyond the periphery thereof, an apron carried by the extended portion of said deflector plate and abutting against the periphery of said disc, driving means for rotating said shaft, and means for connecting said driving means to the conveyor whereby movement of the conveyor operates to rotate the disc.

6. In combination with a loading machine movable over the floor of a mine and having a driven conveyor for transporting material to the rear of the machine, means for discharging the material at a substantial angle to the direction of travel of said conveyor, comprising a substantially vertical shaft rotatably mounted on said machine at the discharge end of and to one side

of the center of said conveyor, a disc carried by said shaft, a deflector plate pivotally mounted on said shaft above said disc and extending beyond the periphery of the latter to deflect the material from said disc toward the side of said machine, means adjacent said disc for receiving the material therefrom, means for driving said shaft to rotate said disc, and means for connecting said driving means to said conveyor whereby the operation of said conveyor controls the rotation of said disc.

7. In combination with a loading machine movable over the floor of a mine, a side discharge mechanism therefor, comprising a rotatable disc, a stationary guide member at one side of said disc and extending a substantial distance around the periphery thereof, a pivoted deflector plate above said disc and projecting therebeyond, said deflector plate being adapted to be moved relative to said disc on contact of the projecting end with an exterior member as the loading machine travels along the mine floor, means for delivering the material onto said disc, and means for rotating said disc.

8. In combination with a loading machine movable along the floor of a mine and having a conveyor for delivering material to the end of said machine, a side discharge mechanism comprising an apron pivoted to said machine at the discharge end of and to one side of the center of said conveyor and extending beyond the side of said machine, a disc between said apron and the discharge end of said conveyor, means for rotating said disc, and means for sweeping the material off of said disc and onto said apron as said disc is rotated.

9. In combination with a self-propelled loading machine movable over the floor of a mine and having an endless conveyor for transporting material to the rear of the machine, a side discharge mechanism for said machine including a rotating disc at the discharge end of said conveyor for receiving the material therefrom, a pivotally mounted apron adjacent said disc and extending beyond the side of said machine, said apron being adapted to be moved around the periphery of said disc on contact thereof with an exterior object as said machine moves over the floor of the mine, means for rotating said disc, and means for sweeping the material from said disc onto said apron.

10. In combination with a loading machine movable over the floor of a mine and having a driven endless conveyor for moving material to one end of said machine, a side discharge mechanism, comprising an apron pivoted to said machine at the discharge end of said conveyor and extending beyond the side of said machine, said apron being movable through an arc on contact thereof with an exterior object as the machine travels along the floor of the mine, a rotatable material receiving member between said apron and the discharge end of said conveyor, and means for transferring the material from said material receiving member onto said apron on rotation of said member.
